GAME APPARATUS

Christopher Metz, Baldwin, N. Y.

Application May 9, 1945, Serial No. 592,853

3 Claims. (Cl. 273—121)

1

This invention relates to improvements in game apparatus and more particularly in bowling game apparatus.

The game apparatus of the invention is generally of the familiar type in which a ball is projected along an alley or surface on which it may be rolled and is then caused to return through a superposed scoring layout so that the direction of travel is reversed. Such games are customarily used in amusement parks, the arrangement having the merit of producing a layout requiring less floor space than one in which the scoring field is level with or aligned with the bowling surface. Such games have the disadvantage that the part played by accuracy is very much reduced. For example, in one familiar type of game, the ball is projected along a surface and is reversed by riding up a semicircular surface against which it is held by centrifugal force and thereafter drops off onto a scoring field. In this type of game, a sudden reversal of direction of rotation of the ball, which is traveling at relatively high velocity, is compelled and the factor of skill is very much reduced. In still other games, the ball is projected onto the scoring field by bouncing or like movement, such as occurs in the popular game of "Skee-Ball," and in such games, the trajectory of the ball is necessarily hard to control.

An object of the present invention is to provide a new and improved arrangement for transferring the ball from the bowling surface to the scoring field in a relatively uniform and predictable manner so that the possibilities for skill may be enhanced.

A further object of the invention is to provide in conjunction with a game apparatus of the type indicated a positive means controllable by the skill of a bowler for determining score.

A still further object of the invention is to provide a game of the bagatelle type in which the element of skill may be increased to any desired extent.

With the foregoing and still other objects which will appear in the following full description in mind, the invention consists in the combinations and arrangements of parts and details of construction which will now first be fully described in connection with the accompanying drawing, and then pointed out more particularly in the appended claims.

In the drawing:

Figure 1 is a plan view of a bowling game apparatus embodying the invention in a preferred form of embodiment;

2

Figure 2 is a central vertical longitudinal section taken on the line 2—2 of Figure 1;

Figure 3 is a section taken on the line 3—3 of Figure 2;

Figure 4 is a section taken on the line 4—4 of Figure 2;

Figures 5 and 6 are vertical cross sections taken on the respective lines 5—5 and 6—6 of Figure 2;

Figure 7 is a detail view on an enlarged scale, looking in the direction of the arrow adjacent the element 18 of Figure 2;

Figure 8 is a wiring diagram; and

Figure 9 is a detail view, on an enlarged scale, of a portion of the apparatus of Figure 2.

The apparatus of the invention comprises a bowling game which is preferably of the approximate size of a so-called "Skee-Ball" layout, but may be widely varied in dimensions and proportions, and is intended primarily for use in amusement parks and the like. The apparatus may conveniently be made in the general form of a cabinet having front and rear walls 1 and 2 and side walls 3, the whole being positioned at convenient height by supports 4 and supporting a bowling board 5, which may be of any suitable material and construction.

The forward end 6 of the bowling board 5, or the end near the player from which the balls are projected is uncovered, and projecting portions of the side walls 3 form side walls therefor, as shown. The bowling board 5 preferably slants upwardly toward the rear and has further upright side wall portions 7 which define a passageway 8, diminishing gradually in width at its throat adjacent the uncovered portion of the bowling surface 5 and being substantially narrower throughout the major part of its length. The passageway 8 is covered by board 9 which preferably extends also across the full width of the apparatus and is supported by the side walls 3.

The board member 9 also forms an upper return board for playing field 10 which is provided with a plurality of bumpers 11 or other suitable devices providing targets for balls. The upper board 9 slants downwardly toward the front of the apparatus and is provided with a port 9a adjacent its far end to permit a ball to pass upward on the curved far end of the bowling surface 5 and thus pass to the upper surface of board 9 where it will roll down on the targets 11 and, after hitting a number of these targets which may vary from zero to any larger number, the ball will roll down to the forward end of the upper surface of the board 9. At the far end the upper board 9 meets the upwardly curved

far end of lower board 5 to both sides of the port 55.

9a. Toward the forward end, the member 9 is slanted slightly transversely of the apparatus so that a ball reaching the lower end will roll crosswise to be received in either of two discharge ports 12 communicating with a return channel 13, which is inclined transversely of the machine and continues longitudinally thereof for returning the balls to playing position.

The playing field 10 is covered by a transparent plate 14 which may be made of glass or suitable plastic material and a suitable housing 15 with a transparent or translucent front 16 is provided at the rear of the machine for containing a suitable scoring board. The specific scoring board forms no part of the present invention but any of the usual boards operating by means of lights or other electrically controlled indicating means may be used.

The far end of the bowling surface extends upward in an arc to a level substantially above the member 9 and is provided with a series of gates 17, 18, 19 and 20. While these gates are shown as four in number, the number of them may be varied as desired within the limits of the space provided within the cabinet. The gate 19, which may be taken as typical of all of the gates, since their construction is similar, is shown in detail in Figure 7 of the drawing. As there shown, the gate may be formed very simply from a single piece of sheet metal which is bent so as to have an upwardly projecting side flange 21 and may be carried by a shaft 22 pivotally mounted in bearings 24 upon the bowling surface 5. Where balls of sufficient size are used, they will ride readily over the shaft 22, and where smaller balls are used, this shaft may be countersunk in the member 5 to avoid undue bouncing. The movement of the gate downwardly from the position of Figure 2 is prevented by means of the bent end 25 of shaft 22, which engages the surface 5 and prevents further movement in this direction, and the gates are yieldingly urged toward this position, as by means of springs 26. A ball striking gate 19 will force it over so it lies flat against the surface 5 and when the ball has passed the gate the spring will return the gate to the position of Figure 2 and prevent the ball from rolling back past it. The ball will thus be caused to roll out to one side or the other onto the surface 5 above the member 9, so that the ball rolls down through the playing field 10. The gates are provided with shoes or depending flanges 23, receivable within slots within playing surface 5 when the gates are down, so as to insure that the balls will roll out to one side or the other and will not rest on the gates. In certain cases where the ball diameter and height of gate are suitably related, however, such provision may be unnecessary. The lowermost gate serves as a trap to prevent any ball which is rolled with sufficient speed from returning to the bowling surface once it has passed the gate and insuring that it will roll back through the playing field instead. As later described, the scoring possibilities of the ball will be determined by how many gates it passes. For example, a ball which passes gate 17 but not gate 18 may be assigned unit scoring, a ball which passes gate 18 may be assigned five times the unit scoring, a ball which passes the gate 19 may be assigned ten times the unit scoring, while a ball which passes the gate 20 may be assigned zero scoring. In this way, higher scoring ratios are provided for more difficult positions and a ball which is

projected with velocity above a certain limit will have no scoring possibility. The specific scoring ratios and the way in which they are distributed among the various gate positions are not critical and may be varied as desired.

In the preferred form of the invention, the largest possible number of gates is included within a cabinet of given dimensions by spacing the gates so closely together that a ball cannot pass one gate and permit it to snap back into the position of Figure 2 without also depressing the next gate to some extent. So long, however, as the succeeding gate is not freed by the ball passing clear of its upper edge, the ball will stop and roll back to the previous gate, and will be deflected to one side or the other by the shoe 23 of the previous gate. Rolling off of a ball at intermediate positions is prevented by the side flanges 21 of the gates. In addition to increasing the compactness of the apparatus, this gate arrangement increases the skill required, since it reduces the margin of error permitted in overshooting a desired gate position, and by varying the distance between gates, the degree of skill required may be controlled. The degree of skill required may be controlled, also, to some extent by regulating stiffness to the gate-restoring springs 26, but undue stiffness in these springs should be avoided, as it may produce a jumping action of the balls, which is undesirable. Lateral displacement of the balls entering the field 10 will be varied by the extent to which it overrides the last gate which it passes and the consequent force with which it strikes the shoe 23 in rolling back.

35 Differential scoring may be provided in a very simple manner by the electrical arrangements shown in Figures 2, 4, 7 and 8. As shown in Figure 7, there may be provided above each gate and in position to be engaged by a ball rolling out 40 from above said gate, a pair of switch actuating members extending through apertures in the surface 5 and operating switches positioned below the bowling surface 5. The switch elements S₂ above gate 18 are shown in Figure 7 and as there shown comprise a pair of spring switch buttons 27 operating the pair of switches S₂ positioned below the surface 5. Similar switches S₁ and S₃ are provided above the respective gates 17 and 19. Thus a ball rolling out from above the gate 17 50 will momentarily close the switch S₁, a ball rolling out from above gate 18 or 19 will temporarily close the switch S₂ or S₃, respectively, and a ball rolling out from above gate 20 will close no switch. As will be understood, the position of the switches 55 in relation to the gates will vary with the pitch of the surface 5 adjacent the gates and also with the configuration of the gates themselves, this position being fixed upon in relation to these factors so as to insure that a ball rolling out from 60 above a given gate will actuate only a switch associated with that gate. By means of the circuit shown schematically in Figure 8, the apparatus may be employed with any of the known scoring boards which provide for different scoring 65 ratios, such a scoring board 28 being indicated diagrammatically in the circuit diagram. Scoring board 28 has a connection 29 to one line 30 of the electric power supply and may be connected to the other power line 31 through either of three connections 32, 33 and 34, so as to determine the scoring ratios. The switches S₁, S₂ and S₃ determine the connection which is established in the following way. Taking the switches S₁ as illustrative, it will be observed that these 70 switches are connected in parallel so that a ball 75

momentarily closing either switch will connect the winding R_1 of a relay associated with these switches to power line 31. The other end of the relay winding is connected through a switch S_4 normally closed to power line 30. The relay being energized, its armature A_1 will close contacts C_1 , thus establishing a connection between the line 32 and the power line 31. The closing of the contact C_1 also establishes through the maintaining connection M_1 a connection parallel to the switches S_1 between the relay winding through contacts C_1 to the power line 31. The relay will therefore remain closed until the connection through its winding is interrupted by the opening of switch S_4 as later described. The relay circuits associated with switches S_2 and S_3 are identified by similar reference characters with corresponding subscripts and require no further description, the momentary closing of the switch S_2 or S_3 as a ball passes over the same operating in a similar way to establish a connection to line 33 or line 34 until this connection is broken by the opening of the switch S_4 . By means of this circuit, three connections providing for three different scoring ratios may be established to the score board 28, depending upon the gate above which the ball rolls out. Should the ball roll out above the uppermost gate 20, no connection will be established and no score will be registered by the score board.

The switch S_4 , previously referred to, is located in the channel 13 so that a ball entering this channel will momentarily open the switch and will thus re-set the circuit for another operation.

The device will normally be coin-operated, having suitable means, such as the slide 35 (Figure 1) for receiving a coin and a coin-operated stop indicated as a pin 36 for releasing balls behind the same upon the insertion of the proper coin. Behind the stop 36 the channel 13 is covered to prevent access to the ball and a portion of this channel in front of the stop is open so as to provide space for the desired number of balls, here shown as five and permit access to the same

after the proper coin has been inserted. The specific coin mechanism utilized is no part of the present invention and accordingly is not further illustrated.

What is claimed is:

1. In a bowling game apparatus, and in combination, a lower bowling board having an upwardly curved far end, an upper playing field return board meeting said lower board part way up the curved far end thereof for receiving balls rolling back thereon and having a port for permitting passage of balls rolling up said curved far end, and means for preventing balls from rolling back through said port.
- 15 2. In a bowling game apparatus, and in combination, a lower bowling board having an upwardly curved far end, an upper playing field return board meeting said lower board part way up the curved far end thereof for receiving balls rolling back thereon and having a port for permitting passage of balls rolling up said curved far end, means for preventing balls from rolling back through said port, and means spaced along said curved far end above said port for deflecting balls laterally thereon at a plurality of successive locations according to their speeds.
- 20 3. Game apparatus according to claim 2, and comprising also scoring field regulating means for varying playing field scores according to the locations at which the balls are deflected.
- 25 35
